(57) **CLAIM**

The ornamental design for a surgical blade cartridge as shown and described.

DESCRIPTION

FIG. 1 is a top, front, right side, perspective view of a surgical blade cartridge;

FIG. 2 is a bottom, rear, left side, perspective view thereof;

FIG. 3 is a top view thereof;

FIG. 4 is a bottom view thereof;

FIG. 5 is a left-side view thereof;

FIG. 6 is a right-side view thereof;

FIG. 7 is an enlarged front view thereof; and,

FIG. 8 is an enlarged rear view thereof.

The broken lines depict portions of the surgical blade cartridge that form no part of the claimed design.

1 Claim, 4 Drawing Sheets
